UNITED STATES PATENT OFFICE.

GEORGE H. GROCE, OF CHICAGO, ILLINOIS, ASSIGNOR TO GENERAL RAILWAY SIGNAL COMPANY, OF GATES, NEW YORK, A CORPORATION OF NEW YORK

SELECTIVE APPARATUS.

1,085,036.

Specification of Letters Patent. Patented Jan. 20, 1914.

Application filed December 7, 1908. Serial No. 466,352.

To all whom it may concern:

Be it known that I, GEORGE H. GROCE, a citizen of the United States, and resident of Chicago, in the county of Cook and State 5 of Illinois, have invented certain new and useful Improvements in Selective Apparatus, of which the following is a specification.

This invention relates to selective apparatus of the kind employed where it is necessary to operate apparatus at a plurality of stations selectively and independently, as, for example, in a telephone system where the call devices at the several stations are to be thus operated.

15 A feature of the novelty of the present invention is found in the fact that the selective mechanism at each station has two "step-by-step" devices; and the selective function is brought about by placing both of these 20 "step-by-step" devices in prescribed positions so that conjoint action of all the selecting devices must occur in order to operate a translating device, such, for instance, as a signal, or call bell. For example, the call 25 for one station may require three steps on one instrument and four on another. That is, if step device No. 1 is moved three steps, and then step device No. 2 is moved four steps, a circuit is formed which includes the 30 call bell. With this device it is obvious therefore that, if each step mechanism is capable of making only, say, six steps, the 35 number of different combinations that can be made with the two will be six times six or thirty-six.

If there should be thirty-six stations on a line equipped with "step-by-step" devices in which only one step mechanism is employed, it would be necessary, in order to 40 call the last station, to produce thirty-six steps in the machine and for this thirty-six impulses over the line would be required. This would always consume much, and usually too much, time. It has been found 45 in practice that since the operator has to produce these impulses by hand, the liability of his making a mistake, when calling more than six or eight, is too great for the necessary certainty. In the present invention, 50 on a line with thirty-six stations, the greatest number that the operator has to count is six,

and the greatest number of impulses that he has to send would be twelve.

In a train despatching system, it is not only necessary that the despatcher be able 55 to call quickly, promptly and surely all of the stations on his line, but it is of great advantage for each station to be able to call the despatcher and to call any other station, on the line. The present system accomplishes all this.

In order to make the "step-by-step" apparatus sure in its operation, there should be some means by which the apparatus can always be returned to its normal or zero 65 position by the calling operator. The present device is so arranged.

In many selective calling devices, the apparatus is so arranged that when a station is called the bell will ring until the operator 70 responds and mechanically restores or breaks the bell circuit. This is an objectionable feature, because a despatcher may try to call an operator within a few minutes after the operator has closed his office. With 75 devices of the character last mentioned, the bell would ring until the operator returned in the morning and the local batteries would be depleted. With the present invention, the length of time that the call bell will 80 ring is under the control of the despatcher or the calling operator. He can ring the bell as long as he pleases and then restore the whole apparatus to its normal position ready for another call.

85 This invention utilizes the telephone wires for operating the call, and two embodiments of the invention are shown, one of which uses neutral relays and the other uses polarized relays. When neutral relays are used, 90 the two circuits necessary for the operation of the selective device are formed by two line wires and ground, the ends of the telephone line are grounded through inductive resistances as usual, and the call bell circuit 95 includes the contact on the two selectors arranged in series. In the polarized system the two telephone wires alone are used for the two circuits and the two different impulses are utilized by means of polarized 100 relays.

In the drawings: Figure 1 is a diagram-

matic view of an apparatus embodying this invention, and showing the mode of connection of the despatcher's office with a series of stations on the line, employing neutral relays; Fig. 2 is a diagrammatic view of the selective apparatus at a station employing neutral relays; and Fig. 3 is a diagrammatic view of the apparatus at a station employing polarized relays.

At each station there is a selective apparatus S, Fig. 1, having two ratchet disks d' and d^2 , Fig. 2, balanced or otherwise arranged to take a normal or zero position automatically, and operated by step magnets s^2 and s' , through the ratchet dogs e' and e^2 . Each ratchet disk is provided with a retaining ratchet dog f' and f^2 , normally acting to prevent backward movement of the disks. When the magnet B is energized, the retaining dogs are disengaged from the ratchets and the disks are free to return automatically to their normal position. Attached to these retaining ratchet dogs are lugs f^2 , f' , that so engage the ratchet dogs e' and e^2 that the latter are capable of independent action, but when the magnet B is energized the ratchet dogs e' and e^2 are also disengaged from the disks. Attached to the armature of each step magnet s' or s^2 is a stop, consisting of an adjustable screw c' or c^2 , so arranged that when the armature is attracted the screw strikes the edge of the ratchet disk, and not only limits the movement of the armature, but clamps the disk and holds it from returning to the normal position so long as the step magnet is energized, and also prevents the disk from moving more than one step at a time. On each ratchet disk is a lug g' or g^2 . Attached to the base of the apparatus and insulated therefrom are contact springs h' and h^2 , so arranged that when the lugs g' and g^2 touch them, an electrical connection is made between the springs h' and h^2 through the frame of the machine. Two circuit breakers j' and j^2 are so arranged that when the disks d' and d^2 are in the normal position the circuits through these circuit breakers will be broken. The object of these circuit breakers will be explained later. Circuit breakers k' and k^2 are also arranged to be operated by the step magnets s' and s^2 respectively. These circuit breakers are normally open and are closed only when the armatures of the step magnets are attracted. There is a normally open circuit breaker l , arranged to be operated by the armature of the releasing magnet B, to close a circuit when the armature of the magnet is attracted.

At each station, in series with the line wires, are relays R' and R^2 . R' is in series with line 1 and R^2 is in series with line 2.

Condensers are placed across the terminals of the two relays so that the relays will not interfere with the talking circuit. At each of the stations are two keys K' and K^2 . When the keys at the despatcher's office are in their normal positions, they connect the line wires 1 and 2 through the inductive resistance r , Fig. 1. The center point of each inductive resistance is connected by wire to ground. When either one of these keys K' or K^2 is closed, the battery M is connected to the line wire controlled by that key, and the circuit is formed from the battery M through this linewire and through each of the corresponding line relays at the different stations, and returns to the battery M by way of the ground. So that, if key K' is closed once, all the line relays R' on the line 1 will be energized once and each one establishes a circuit at its local station through the battery L, which energizes the step magnet s' and thereby advances the ratchet disk d' one step. If the same key is closed again, the same effects occur and the step disk is advanced another step. In the same way, when the key K^2 is closed, all of the line relays R^2 on the line 2 at the different stations are energized, and each forms a local circuit which energizes the step magnet s^2 and thereby advances the ratchet disk d^2 one step. In other words, each closing of a key advances its series of step magnets one step.

Supposing now that the call for the station shown in Fig. 2 is three steps on d' and four steps on d^2 . The method of operating is to close the key K' twice. This steps the disk d' up two steps. Then the key K^2 is closed three times, which steps the disk d^2 up three steps. Now the two keys are closed simultaneously and are held. This steps up both ratchets one more step, which brings the lug g' into contact with the contact spring h' , and the lug g^2 into contact with the contact spring h^2 . Now as long as the keys are held closed, a local circuit is formed at this particular station which, starting from the battery L, consists of the wire 21, the bell b, wire 22, spring h' , lug g' , the frame of the machine, lug g^2 , spring h^2 , wire 3, circuit closer k^2 (which is closed because the magnet s^2 is energized), wire 4, circuit controller k' , (which is also closed because step magnet s' is energized), wire 5, wire 6, back to battery. This energizes the bell b which remains energized as long as the circuit closers k' and k^2 are closed, or as long as the two keys K' and K^2 are held closed. At the same time that this local circuit is formed, another circuit is established which starts from the battery L, through wire 7, magnet B, wire 8, wire 3, circuit controller k^2 , wire 4, circuit controller k' , wire 5, back to battery. This en-

ergizes the releasing magnet B and releases the ratchet dogs e' , f' , e^2 and f^2 so that the disks d' and d^2 are free to return to their zero or normal position; but the screws c' and c^2 on the armatures of the step magnets engage the edges of the disks, and the disks are held in their set positions. The bell b therefore rings, as stated above, as long as the magnets s' and s^2 are kept energized simultaneously. Still another circuit was formed when the magnet B was energized. This circuit starting from the battery L, consists of the wire 7, the magnet B, wire 8, circuit controller l , (which is now closed), wire 9, wire 10, circuit controller j' (which is now closed because the disk d' is away from its normal position), wire 11 and wire 5 back to battery. This same circuit can also be completed by the way of wire 9, and 10, and circuit controller j^2 and wire 12, 11, 5 and 6 back to battery. The object of this latter double circuit is to keep the magnet B energized and to hold the ratchet dogs out of engagements, until both of the disks d' and d^2 have returned to their normal positions.

As soon as the keys K' and K^2 are released and have returned to their normal positions, the magnets s' and s^2 are demagnetized, and the disks d' and d^2 are free to return to their zero positions. As soon as these disks start toward their zero positions, the contacts of the springs h' and h^2 are broken and the bell ceases to ring. When the disks have fully returned to their normal positions, the circuit controllers j' and j^2 are opened, thus demagnetizing the magnet B and allowing the ratchet dogs to assume their normal positions. It will be noted that at any time when the two step magnets of a machine are energized simultaneously, the releasing magnet is also energized; and consequently when both keys are in the normal position all of the selecting mechanisms return to their normal positions. This particular feature is important because, should any one of the selective devices of the system get out of step, they can all be returned to their zero positions by closing the two call keys simultaneously and then releasing them.

In order to provide means by which any station can call the despatching station, or by which any station can call any other station, a calling battery N is provided, one pole of which is connected to the ground. Two other keys K^3 , K^4 , are also provided at each station, which operate circuit controllers k^3 , k^4 . For example, when both keys K^3 and K^4 are in their normal position, the circuit of line wire 1 from the right is connected through to line wire 1 of the line, and likewise line wire 2 is connected through from left to right. These circuit controllers when in their normal positions, also cut off

the battery N from either of the keys K' or K^2 , so that if either K' or K^2 should be inadvertently closed, the battery N would not be connected to either line. The circuit controllers operated by these keys K^3 and K^4 are also arranged so that when K^3 is closed, the line wires 1 and 2 to the right will be cut off from the line, and wires 1 and 2 to the left will be left in position to be connected to batteries by means of the keys K' and K^2 . Therefore when an operator wishes to call another operator, located to the left of him say, he first presses the key K^3 . This cuts off the line to the right and connects the battery to his calling keys. He then operates the calling keys K' and K^2 in the same manner as described above, and thus calls the station he desires. When he releases the key K^3 , the line returns to its normal condition, that is, it is connected through his station. If the operator wishes to call the station to the right of him, he closes his key K^4 , which cuts off the line to the left and connects his calling keys to the lines to the right. In some stations there might be more than one telephone line, and it is obvious that this calling apparatus last described can be used for calling on any line by using the ordinary telephone jacks, so that the calling apparatus may be plugged in to the line on which it is desired to call.

Fig. 3 shows the equipment of a station that is operated by the polarized system. In this, all stations on the line, including the despatcher's station if necessary, can be identical; the only difference being that at the end station, the power ends of the lines 1 and 2 are connected by an inductive resistance. In this case, as in the other, the polarized relay R^{10} is in series with line wire 1 and, when it is operated energizes the step magnet s' ; and likewise the polarized relay R^{20} , in series with the line wire 2, when operated by the current of the proper polarity, energizes the step magnet s^2 . The selecting apparatus S is identical with the form employing neutral relays, except that two circuit controllers have been added. One, n' , is arranged to be closed when the step magnet s' is energized and the other m^2 is arranged to be closed when the ratchet disk d^2 leaves its zero position. The polarity of the line relays R^{10} and R^{20} , and the connections to the keys K^{10} and K^{20} , are so arranged that when the key K^{10} is closed, current sent through the lines 1 and 2 is of the proper polarity to operate the relay R^{10} , and when K^{20} is closed the polarity of the current sent through the lines is suitable to operate the relay R^{20} . With this polarized system, the method of handling the calling keys is slightly different from the method employed with neutral relays. For example, the call for the station shown in Fig. 3 is three steps

on d' and four steps on d^2 . The operator who desires to call this station will first close his key K^{30} . The key K^{30} in its normal position simply connects the line wire 2 through the station at which this key is located. When this key is closed, it connects the line with the keys K^{10} and K^{20} ; but not in such a way that, when the keys K^{10} and K^{20} are in their normal position, there is any battery supplied to the line. The operator, therefore, who desires to call, closes his key K^{30} and holds it closed. He then closes the key K^{10} , in this case twice. That energizes the line relays R^{10} , so that they close the local circuit to the step magnets S' and step up the disk d' two steps. The operator then closes the key K^{20} three times. This energizes the line relays R^{20} , and through the local circuit the step magnet s^2 , and steps up the disk d^2 three steps. Now returning to the key K^{10} , he closes it once and holds it closed. This again energizes the relays R^{10} and also the step magnets s' , and steps up the disk d' one more step, making three in all. When the magnet s' is thus energized, another circuit is formed which, starting from the battery I_4 , is composed of the wire 23, wire 24, circuit controller n' , which is now closed, wire 3, circuit controller m^2 , which is now closed because the disk d^2 has been stepped up three steps, wire 4, wire 5, through the magnet s^2 and wire 6 back to battery. This energizes the step magnet s^2 and steps up the disk d^2 another step, making four in all. Now, as long as the key K^{10} is held closed, both the step magnets s' and s^2 will be energized, and by the pressure of the adjusting screws e' and e^2 against the disks, the disks will be held in this particular position. And just as in the other system, this position of the disks brings the spring h' into contact with the lug g' and the lug g^2 into contact with the spring h^2 and establishes the circuit for the bell b ; and the energizing of both the step magnets s' and s^2 forms a circuit for energizing the releasing magnet B ; and the ratchet dogs are held out of engagement. As soon as the magnet B is energized, the circuit controller l is closed which closes another circuit for the magnet B , which latter circuit is controlled by circuit controllers j' and j^2 , so that the magnet B will not be deenergized until the ratchet disks have returned to their normal positions. The releasing of the key K^{10} deenergizes the line relays R^{10} and consequently the step magnets s' and s^2 , and the bell stops ringing; and when the disks have returned to their normal positions, the circuit through the releasing magnet B is broken, and ready for the next call. With this system, in order to restore all the selectors to zero without calling any station, it is necessary to have one of the thirty-six

combinations devoted entirely to this purpose:—for example, one step on d^2 and two steps on d' . The closing of the key K^{10} once and then K^{20} once, and then K^{10} again, results in energizing the releasing magnets B without ringing any bell, and when the key K^{10} is released the apparatus returns to its normal position. It will be understood, of course, that while an operator is calling, he must hold his key K^{30} closed, and as soon as he has finished his call he releases the key K^{30} and thus connects the talking circuit through his station.

My invention is not limited to the embodiment thereof hereinbefore described and illustrated in the accompanying drawings, but may be embodied in various forms within the nature of the invention as it is defined in the succeeding claims.

What I claim is:

1. The combination of a plurality of selectors; selectively-operable devices for controlling the movement of the selectors either independently or simultaneously from a distance; a translating device responsive to the conjoint action of all the selectors; and means including a device to be electrically energized for restoring the selectors to normal position.

2. The combination of a plurality of electric selectors; selectively-operable devices for controlling the movement of the selectors either independently or simultaneously from a distance; a translating device responsive to the conjoint action of all the selectors; and means including a device to be electrically energized for restoring the selectors to normal position.

3. The combination of a plurality of electric selectors; a controlling circuit for each selector; an independently operable controller for each circuit; a translating device responsive to conjoint action of all the selectors; and means including a device to be electrically energized for restoring the selectors to normal position.

4. The combination of a plurality of selectors, each having an electrical contact; a circuit having therein all said contacts arranged in series; selectively-operable devices for controlling the movement of the selectors either independently or simultaneously from a distance; a translating device in said circuit; a source of energy in said circuit; and means including a device to be electrically energized for restoring the selectors to normal position.

5. The combination of a plurality of selectors, each having an electrical contact; selectively-operable devices for controlling the movement of the selectors either independently or simultaneously from a distance; a translating device responsive to the conjoint action of all the contacts; and

- means including a device to be electrically energized for restoring the selectors to normal position.
6. The combination of a plurality of electric selectors, each having an electrical contact; a controlling circuit for each selector; an independently-operable controller for each circuit; a circuit opened and closed on conjoint action of all the contacts; a translating device controlled by said circuit; and means including a device to be electrically energized for restoring the selectors to normal position.
7. The combination of a plurality of 15 selectors; selectively-operable devices for controlling the movement of the selectors either independently or simultaneously from a distance; a translating device responsive to conjoint action of all the selectors; means for holding the selectors in the position they are placed by the action of their controlling devices; and means including a device to be electrically energized for restoring the selectors to normal position.
- 20 8. The combination of a plurality of electric selectors; selectively-operable devices for controlling the movement of the selectors either independently or simultaneously from a distance; a translating device responsive to conjoint action of all the selectors; means for holding the selectors in the position they are placed by the action of their controlling devices; and means including a device to be electrically energized for restoring the 25 selectors to normal position.
9. The combination of a plurality of electric selectors; a controlling circuit for each selector; an independently-operable controller for each circuit; a translating device 30 responsive to conjoint action of all the selectors; means for holding the selectors in the position they are placed by the action of their controllers; and means including a device to be electrically energized for restoring the 35 selectors to normal position.
10. The combination of a plurality of 40 selectors, each having an electrical contact; a circuit having therein all said contacts arranged in series; selectively-operable devices for controlling the movement of the 45 selectors either independently or simultaneously from a distance; a translating device in said circuit; a source of energy in said circuit; means for holding the selectors in the position they are placed by the action of their controlling devices; and means including a device to be electrically energized for restoring the 50 selectors to normal position.
- 55 11. The combination of a plurality of 55 selectors, each having an electrical contact; selectively-operable devices for controlling the movement of the selectors either independently or simultaneously from a dis-
- tance; a translating device responsive to 65 conjoint action of all the contacts; means for holding the selectors in the position they are placed by the action of their controlling means; and means including a device to be electrically energized for restoring the 70 selectors to normal position.
12. The combination of a plurality of electric selectors, each having an electrical contact; a controlling circuit for each selector; an independently-operable controller for 75 each circuit; a circuit closed on conjoint action of all the contacts; a translating device controlled by said circuit; means for holding the selectors in the position they are placed by the action of their controlling 80 means; and means including a device to be electrically energized for restoring the 85 selectors to normal position.
13. In a selective telephone calling mechanism; the combination of a plurality of electric selectors, each having a contact adapted to be made when the selector is in a pre-determined position; a plurality of controlling circuits, one for each selector; a plurality of independently-operable controllers, 90 one for each controlling circuit; a calling signal; means controlled by said contacts for operating the same on conjoint action of all the selectors; and means including a device to be electrically energized for restoring the 95 selectors to normal position.
14. In a selective telephone calling mechanism; the combination of a plurality of electric selectors, each having a contact adapted to be made when the selector is in a pre-determined position; a plurality of controlling circuits, one for each selector; a plurality of independently-operable controllers, 100 one for each controlling circuit; a calling signal; a circuit controlling the signal and 105 including all said contacts arranged in series; a source of energy; and means including a device to be electrically energized for restoring the 110 selectors to normal position.
15. In a selective telephone calling mechanism; the combination of a plurality of electric selectors, each having a contact adapted to be made when the selector is in a pre-determined position; a plurality of controlling circuits, one for each selector; a plurality of independently-operable controllers, 115 one for each controlling circuit; a calling signal; means for operating the same on conjoint action of all the selectors; means for holding the selectors in the position they 120 are placed by the action of their controllers; and means including a device to be electrically energized for restoring the 125 selectors to normal position.
16. In a selective telephone calling mechanism; the combination of a plurality of electric selectors, each having a contact adapted to be made when the selector is in a pre-

determined position; a plurality of controlling circuits, one for each selector; a plurality of independently-operable controllers, one for each controlling circuit; a calling signal; a circuit including all said contacts arranged in series; a source of energy; means for holding the selectors in the position they are placed by the action of their controllers; and means including a device to be electrically energized for restoring the selectors to normal position.

17. The combination of a plurality of movable electric contact makers; an electric driving mechanism for each contact maker; a separate controlling circuit for each driving mechanism; a controller for each controlling circuit; a translating device; a circuit therefor comprising all said contacts in series; a source of energy; and means for disconnecting said driving mechanism from the contact makers on simultaneous action of a plurality of said controllers.

18. The combination of a plurality of movable electric contact makers; an electric driving mechanism for each contact maker; a separate controlling circuit for each driving mechanism; a controller for each controlling circuit; a translating device; a circuit therefor comprising all said contacts in series; a source of energy; a device for disengaging all the driving mechanisms; and a circuit controlled by a plurality of said contact makers for energizing said last mentioned device on conjoint operation of a predetermined plurality of said controllers.

19. The combination of a plurality of movable electric contact makers; an electric driving mechanism for each contact maker; a separate controlling circuit for each driving mechanism; a controller for each controlling circuit; a translating device; a circuit therefor comprising all said contacts in series; a source of energy; a restoring device for disengaging all the driving mechanisms; a circuit controlled by a plurality of said contact makers for energizing said restoring device on conjoint operation of a predetermined plurality of said controllers; stops governed by the respective controlling circuits for holding each contact maker in set position when its driving mechanism is disengaged; and means for releasing said stops to allow the contact makers to assume normal position.

20. The combination of a plurality of movable electric contact makers; a pawl and ratchet mechanism for each contact maker; an electromagnetic motor for actuating each pawl and ratchet mechanism; a separate controlling circuit for each motor; a controller for each controlling circuit; a translating device; a circuit therefor comprising all said contact makers in series; a source of energy; and means for disconnecting said

pawl and ratchet mechanism from the contact makers on simultaneous action of a predetermined plurality of said controllers.

21. The combination of a plurality of movable electric contact makers; a pawl and ratchet mechanism for each contact maker; an electromagnetic motor for actuating each pawl and ratchet mechanism; a separate controlling circuit for each motor; a controller for each controlling circuit; a translating device; a circuit therefor comprising all said contact makers in series; a source of energy; a restoring device for disengaging all the pawl and ratchet mechanisms; and a circuit controlled by a plurality of said contact makers for energizing said restoring device on conjoint operation of a predetermined plurality of said electro-magnetic motors.

22. The combination of a plurality of movable electric contact makers; a pawl and ratchet mechanism for each contact maker; an electromagnetic motor for actuating each pawl and ratchet mechanism; a separate controlling circuit for each motor; a controller for each controlling circuit; a translating device; a circuit therefor comprising all said contact makers in series; a source of energy; a restoring device for disengaging all the pawl and ratchet mechanisms; a circuit controlled by a plurality of said contact makers for energizing said restoring device on conjoint operation of a predetermined plurality of said electro-magnetic motors; stops governed by the respective controlling circuits for holding each contact maker in set position when its pawl and ratchet mechanism is disengaged; and means for releasing said stops to allow the contact makers to assume normal position.

23. A selective system comprising a plurality of stations; each station being provided with selective apparatus having, in combination, a plurality of electrically-actuated selectors having a step-by-step operation in response to successive electrical impulses and an electric translating device operated by the selectors jointly and only upon the attainment by each selector of a predetermined position; means for transmitting to all said stations a series of electrical impulses to operate similarly the selectors in all of the stations, the translating devices at the several stations being arranged and connected to respond to different predetermined positions of their respective selectors so that the translating devices may be operated selectively according to the number of electrical impulses transmitted.

24. In a selector instrument, a plurality of movable members, a source of current, means operated by separate current impulses from said source to move said members independently step by step to certain predetermined

positions, means to hold the members in their moved positions as they are advanced step by step, and means governed by the first named means to release said members from the second named means.

25. In a selector instrument, a plurality of movable members, a source of current, means operated by separate current impulses to move said members independently step by 10 step to certain predetermined positions, means to hold the members in their moved positions as they are advanced step by step, and means governed by the first named means to release said members from the second named means, and means to retain said last named means operative until the full return of each movable member to normal position.

26. In a selector instrument, a plurality of 20 movable members, means to move said members independently step by step, means for holding the members in moved position, an open circuit including an electrical device and a source of energy, means associated 25 with each movable member adapted to cooperate for closing said open circuit, said means placed in operative position by a predetermined step by step movement of each movable member and means for restoring 30 said members to initial position.

27. In a selector instrument, a plurality of movable members, separate means for imparting a step by step movement to each member, said movable members having a 35 normal position and a plurality of operated positions, means to hold said movable members in operated position and means governed by the simultaneous action of said separate means to release said movable members from any operated position thus allowing 40 them to return to normal position.

28. In a selector, a source of current, an indicator in a normally open circuit with said source of current, two pivoted members, means for rotating the pivoted members through any desired angle, means operated by a predetermined rotation of both the pivoted members for closing said normally open circuit, means for holding said pivoted 45 members in moved position, and means for releasing said holding means.

29. In a selector, a source of current, an indicator in a normally open circuit with said source of current, two pivoted members, 50 means for rotating the pivoted members through any desired angle, means operated by a predetermined rotation of both the pivoted members for closing said normally open circuit, means for holding said pivoted members in moved position, and means including a device to be electrically energized for releasing said holding means.

30. In a selector, an electro-magnet, means to energize the electro-magnet, an armature

governed by the electro-magnet, a pivoted 65 member, means governed by the armature for rotating the pivoted member through any desired angle, another electro-magnet, means to energize the other electro-magnet, an armature governed by the other electro-magnet, 70 another pivoted member, means governed by the armature of the second said electro-magnet for rotating the other said pivoted member through any desired angle, a source of current, a signal, a normally open 75 circuit including said source of current and said signal, means governed by each pivoted member for partially closing said open circuit, means for holding said pivoted members in moved position, and means for restoring 80 said pivoted members to initial position.

31. In a selector, an electro-magnet, means to energize the electro-magnet, an armature governed by the electro-magnet, a pivoted 85 member, means governed by the armature for rotating the pivoted member, another electro-magnet, means to energize the other electro-magnet, an armature governed by the other electro-magnet, another pivoted member, means governed by the armature of the second said electro-magnet for rotating the other said pivoted member, a source of current, a signal, a normally open circuit including said source of current and said signal, 90 means governed by one of said pivoted members for partially closing said normally open circuit, means governed by the other of said pivoted members for then completely closing said normally open circuit, 95 means for holding said pivoted members in rotated position, and means for restoring said pivoted members to initial position.

32. In a selective device, a source of current, an indicator included in a normally 101 open circuit with said source of current, two independently pivoted members, means for independently rotating the members, means for closing said normally open circuit by a selective movement of each of said members, 110 means for holding said pivoted members in moved position, and means for restoring said pivoted members to initial position.

33. In a selective device, a source of current, an indicator, said indicator included 115 in a normally open circuit with said source of current, two normally open contacts in said normally open circuit, a pivoted sector, means operated by a predetermined movement of said sector for closing one of said normally open contacts, another pivoted sector, means operated by a predetermined movement of the other of said sectors for closing the other of said normally open contacts, means for operating both of said sectors, 120 and holding them in operated position, and means for restoring the sectors to initial position.

34. In a selective device, a source of current, an indicator, said indicator included in a normally open circuit with said source of current, two normally open contacts in said normally open circuit, a pivoted sector, means operated by a predetermined movement of said sector for closing one of said normally open contacts, another pivoted sector, means operated by a predetermined movement of the other of said sectors for closing the other of said normally open con-

tacts, two other normally open contacts in said normally open circuit, means for rotating each of said sectors, and means operated simultaneously with the operation of the 15 sectors for closing the two other normally open contacts.

GEORGE H. GROCE.
